UNITED STATES PATENT OFFICE

WILLIAM J. DAVIS, OF WINDFALL, INDIANA, ASSIGNOR TO JOHN F. HEATH, OF TIPTON, INDIANA

FENCE PROTECTOR

Application filed October 11, 1930. Serial No. 488,007.

This invention relates to a support for a fence guard.

The chief object of this invention is to provide a support for a guard strand to be positioned adjacent a fence to protect the latter, which support may be readily attached to the fence and supported thereby and attached to the guard strand and support the same in predetermined position.

10 The chief feature of the invention consists in the mounting upon a fence of a brace type support for a guard or fence protecting strand which will maintain the strand in predetermined position and prevent undue movement of the strand from said predetermined position either upwardly, downwardly, inwardly or outwardly.

Another feature of the invention consists in the ready attachability and detachability 20 of the brace type support.

The full nature of the invention will be understood from the accompanying drawings and the following specifications and claims:

25 In the drawings, Figure 1 is a perspective view of a portion of a fence and a guard strand adjacent thereto and supported in spaced and predetermined relation to the fence by one of the brace type supports.

30 Figure 2 is a similar view of a modified form of the invention, modifying the brace type support.

Figure 3 is a similar view of a still further modified form of the invention.

35 In the drawings, 10 indicates the top strand of a fence having at least two lower strands 11 and 12 in spaced relation and said strands may be considered to be substantially horizontally positioned. A vertically positioned base 14 at its upper end is provided with a pair of U-shaped portions

40 15 and 16, connected by the transverse portion 17, the free end being indicated at 18. The U-shaped construction thus is adapted to ride upon the top strand 10 of the fence and, as herein shown, the vertical base portion lies to one side of strand 11 and upon the opposite side of strand 12.

45 50 Herein, the base portion terminates in an eye or loop 19 and swivelly connected there-

to is a similar eye 20 carried by the lower end of the brace rod portion 21. Said brace rod portion terminates in the U-shaped loop 22 which may or may not support the guard strand 13 for maintaining the same in predetermined relation. Herein an arm portion 23 is detachably and interlockingly associated with the multiple loop of the base portion through the U-shaped loop formation 24 which is interlockingly associated with the base portion and the upper strand and serves to lock the same thereto.

The outer end of the substantially horizontally positioned arm 23 terminates in a scroll type loop 25 that receives and supports the protecting strand 13. The loop is interlockingly associated with the U-shaped loop 22 of the brace rod.

The fence strands and the guard strand are herein shown as plain wire but may be of barbed wire or twisted wire without departing from the invention.

In Figure 2 of the invention the fence and protecting strand bear like numerals as in Figure 1 but the triangular support construction is indicated by numerals of the one hundred series. Thus 114 indicates the base rod which is similarly positioned and hingedly connects through the portions 119 and 120 at its lower end to the lower end of the brace rod 121, which intermediate its ends is provided with a U-shaped portion 121a. The arm 123 herein is shown terminating in a U-shaped loop 122 and the brace rod at its upper end terminates in a scroll or eye formation 125. In this form of the invention, therefore, the U-shaped loop and the scroll or coil portion which are interlockingly associated together, are interchanged relative to the arm and the brace, although the guard strand is supported by the arm.

In the present form of the invention, the upper end of the vertical base includes the loop portion 124 which is interlockingly associated with the loop portion 116 and tongue portion 117 carried by the arm 123. The tongue portion 117 is interlockingly associated with the loop 124 just as the tongue portion 24 in the modification shown in Fig-

ure 1 is interlockingly associated with the loops 15, 16 and 17 of the vertical base. In this form of the invention, therefore, the tongue portion is carried by the arm al-
5 though the form of the interlocking connection is reversed and the multiple contact upon the fence strand 10 is obtained through the arm end in Figure 2, whereas it is obtained through the base portion in
10 **Figure 1.**

In assembling the modification of the invention shown in Figure 2, the base portion 114 and arm 123 are placed in the position shown. The guard wire 13 is then placed
15 in the U-shaped loop 122 and the end of the scroll formation 125 is brought to a position above the said guard wire. The brace member 121 is then rotated about its connection with the base wire 114 by means
20 of the U-shaped portion 121a to advance the scroll formation 125 in the manner of a screw thread to the position shown in the drawing. Thus the assembling of the device is rapidly and easily accomplished.

25 In Figure 3 a still further modified form of the invention is illustrated, wherein the vertical base portion 214 terminates in an eye portion 219 with an extension 220 that is interlockingly connected to the brace portion 221 as at 221a.

30 The upper end of the brace portion includes the U-shaped loop 222 while the outer end of the arm 223 terminates in the loop 225 which receives the protecting strand 13 substantially similar to the construction of
35 Figure 1. The adjacent ends of the arm 223 and the base 214 are interlockingly associated with the fence strand 10 by the portions indicated by the numerals 215, 216 and
40 217 carried by the base and the portions 224 and 224a carried by the arm.

45 The invention claimed is:

1. The combination with a wire fence having at least three substantially horizontal strands and a protecting guard strand to be sustained in spaced relation thereto, of a sustaining support including a vertical base, an outwardly-directed arm, said base and arm having a detachable and interlocking connection with each other and with the uppermost of the three strands, said base extending upon opposite sides of the two lower strands, and brace means connected to the lower end of the base and interlockingly and detachably connected to the outer end of the arm, the latter connection supporting the guard strand.
50

55 2. A device as defined by claim 1, characterized by the guard strand supporting end of the arm including a loop for receiving the guard strand.

60 3. A device as defined by claim 1 characterized by the adjacent interlocking ends of the arm and base comprising a pair of interlocking U-shaped portions, one of

which nests the adjacent fence strand and the other of which traps the strand therein.

4. A device as defined by claim 1 characterized by the guard strand supporting end of the arm including a loop for receiving the guard strand, and the adjacent interlocking ends of the arm and base comprising a pair of interlocking U-shaped portions, one of which nests the adjacent fence strand and the other of which traps the strand therein.
70

5. A device as defined by claim 1 characterized by the base and brace including a hinge-like connection therebetween.
75

6. A device as defined by claim 1 characterized by the guard strand supporting end of the arm including a loop for receiving the guard strand, and the base and brace including a hinge-like connection therebetween.
80

7. A device as defined by claim 1 characterized by the adjacent interlocking ends of the arm and base comprising a pair of interlocking U-shaped portions, one of which nests the adjacent fence strand and the other of which traps the strand therein, and by the base and brace including a hinge-like connection therebetween.
85

90 8. A device as defined by claim 1 characterized by the guard strand supporting end of the arm including a loop for receiving the guard strand, the adjacent interlocking ends of the arm and base comprising a pair of interlocking U-shaped portions, one of which nests the adjacent fence strand and the other of which traps the strand therein, and by the base and brace including a hinge-like connection therebetween.
95

100 9. The combination with a wire fence having at least two substantially horizontal strands and a protecting guard strand to be sustained in spaced relation thereto, of a sustaining support including a substantially vertical base, an outwardly-extending arm, said base and arm having a detachable and interlocking connection with each other and with one of said horizontal strands and said base engaging another of said horizontal strands for support thereby, a U-shaped portion formed on the outer end of said arm for receiving said guard strand, and a brace member having a rotatable connection with the lower end of said base and a scroll formation on its upper end engageable with said U-shaped portion to lock said guard strand therein by rotation of said brace member about said rotatable connection.
105

110 10. The combination with a wire fence having at least two substantially horizontal strands and a protecting guard strand to be sustained in spaced relation thereto, of a sustaining support including a substantially vertical base, an outwardly-extending arm, said base and arm having a detachable
115

120

125

130

and interlocking connection with each other and with one of said horizontal strands and said base engaging another of said horizontal strands for support thereby, a U-shaped portion formed on the outer end of said arm for receiving said guard strand, a brace member having a rotatable connection with the lower end of said base and a scroll formation on its upper end engageable with said U-shaped portion to lock said guard strand therein by rotation of said brace member about said rotatable connection, and means formed upon said brace member for effecting said rotation.

15 In witness whereof, I have hereunto affixed my signature.

WILLIAM J. DAVIS.
